[57] CLAIM

The ornamental design for a “watch casing and bezel”, as shown and described.

DESCRIPTION

FIG. 1 is a perspective view of a watch casing and bezel showing our new design;

FIG. 2 is a left side elevational view thereof;

FIG. 3 is a top plan view thereof;

FIG. 4 is a right side elevational view thereof;

FIG. 5 is a front elevational view thereof;

FIG. 6 is a rear elevational view thereof;

FIG. 7 is a bottom plan view

FIG. 8 is a perspective view of a watch casing and bezel in accordance with an alternate embodiment of our invention; FIG. 9 is a left side elevational view of this alternate embodiment;

FIG. 10 is a top plan view of this alternate embodiment; FIG. 11 is a right side elevational view of this alternate embodiment;

FIG. 12 is a front elevational view of this alternate embodiment;

FIG. 13 is a rear elevational view of this alternate embodiment; and,

FIG. 14 is a bottom plan view of this alternate embodiment.
